UNITED STATES PATENT OFFICE.

WILFRID G. CHAUSSÉ, OF DETROIT, MICHIGAN.

DISTRIBUTER FOR VAPOR-BURNERS.

1,321,981.

Specification of Letters Patent.

Patented Nov. 18, 1919.

Application filed February 17, 1919. Serial No. 277,590.

To all whom it may concern:

Be it known that I, WILFRID G. CHAUSSÉ, a citizen of the United States of America, residing at Detroit, in the county of Wayne 5 and State of Michigan, have invented certain new and useful Improvements in Distributers for Vapor-Burners, of which the following is a specification, reference being had therein to the accompanying drawings.

10 In my pending application filed April 11, 1918, Serial No. 161,381 there is disclosed a novel distributor for a vapor burner, and this invention is an improvement on my former distributor as I accomplish better 15 results and employ standard material in the construction of the distributor.

This invention also includes novel tie brackets adapted for supporting the distributor in proximity to the rail or other 20 track equipment to be heated, and all the construction entering into the improvement will be hereinafter described and then claimed.

Reference will now be had to the drawing, 25 wherein—

Figure 1 is a plan of a portion of a track equipment provided with a heater in accordance with my invention;

Fig. 2 is a horizontal sectional view of 30 the heating device, partly broken away;

Fig. 3 is a cross sectional view of the same, showing the manner of supporting the heater relative to a tie and a rail, and

Fig. 4 is a perspective view of a tie 35 bracket.

A heater in accordance with my invention comprises a conduit or tubular member 1 that may be of any desired length, and this tubular member may be constructed of 40 cast iron with opposed walls thereof provided with tie rod or bolt openings 2 and one of said walls with a series of jet openings 3.

In the openings 2 are placed transverse 45 tie rods or bolts 4 having the outer ends thereof provided with spacing members or sleeves 5 and nuts 6.

On the outer ends of the bolts 4, between the sleeves 5 and the nuts 6, is a longitudinally disposed angle bar having one flange 7 thereof disposed in a vertical plane, at a right angle to the axes of the bolts 4 and its other flange 8 in a horizontal plane projecting toward the tubular conduit 1, so as 55 to coöperate therewith in forming an oblong hood having its bottom open.

One end of the tubular conduit 1 is provided with a cap 9 having openings 10 and connected to said cap is a rotary shutter 11 coöperating with said cap in providing a 60 damper adapted to regulate the draft through the tubular conduit and the admission of air to sustain combustion within said conduit. Detachably connected to the opposite end of the tubular conduit is a 65 conventional form of burner including a casting 12 having suitable openings to admit air and sustain combustion, a fuel supply pipe 13, a heater coil 14 and a burner 15. This burner is adapted to project a flame 70 into the tubular conduit 1 and said flame will pass through the openings 3 and provide a series of jets within the hood formed by the angle bar attached to the side of said conduit. 75

As shown in Figs. 1 and 3, the heater has been designed for preventing the accumulation of ice and snow at a switch rail, tongue or other track equipment, and in order that the heater may be properly supported, ties 16 in proximity to the rail 17 are provided with two part brackets, one part of each bracket providing a supporting member 18 and the other part of the bracket a clamping member 19, said bracket parts 80 65 being suitably connected together, as at 20, and to the ties 16, as at 21. These brackets represent suitable means for supporting the heater relative to the ties, and in some instances the heater may be provided with a 90 nozzle 22 extending to other parts of a switch so as to conduct heat or flame thereto and thus prevent the elements from interfering with the operation of the track equipment. 95

Any suitable source of fuel may be employed for the burner, and I would have it understood that the structural elements of the heater are susceptible to such changes as fall within the scope of the appended 100 claims.

What I claim is:—

1. A heater of the type described comprising a conduit, a burner at one end thereof adapted to direct a flame into said 105 conduit, a damper mounted on the opposite end of said conduit, said conduit having an apertured wall, and an angle bar connected to said conduit adjacent the apertured wall thereof and having a lateral flange extending toward said conduit. 110

2. A heater of the type described com-

prising a perforated conduit, bolts extending therethrough, an angle bar supported by said bolts adjacent the perforations of said conduit and providing a hood, and heat 5 supplying means for said conduit.

3. A heater of the type described comprising a conduit having an apertured wall, a burner at one end of said conduit, a damper at the opposite end thereof, bolts trans- 10 versely of said conduit, an angle bar sup-

ported by said bolts against the apertured wall of said conduit and providing a hood longitudinally thereof, and supporting means for said conduit.

In testimony whereof I affix my signature in the presence of two witnesses.

WILFRID G. CHAUSSE.

Witnesses:

ANNA M. DORR,

KARL H. BUTLER.
